UNITED STATES PATENT OFFICE.

JOHN P. MCLEOD, OF CHICAGO, ILLINOIS, ASSIGNOR OF ONE-HALF TO
HERMAN F. VOSHARDT, OF CHICAGO, ILLINOIS.

FURNACE.

No. 823,962.

Specification of Letters Patent.

Patented June 19, 1906.

Application filed September 16, 1905. Serial No. 278,695.

To all whom it may concern:

Be it known that I, JOHN P. MCLEOD, a citizen of the United States, residing at Chicago, in the county of Cook and State of Illinois, have invented new and useful Improvements in Furnaces, of which the following is a specification, reference being had to the accompanying drawings, forming a part thereof.

The purpose of this invention is to provide an improved furnace particularly designed for steam-boilers for the purpose of improving combustion and preventing any combustible products of the fuel being carried off in the smoke.

15 It consists of the features of construction set out in the claims.

In the drawings, Figure 1 is a partly-sectional front elevation of a structure embodying my improvements, section being made longitudinally of the fire-box and certain pipes being broken away and shown in axial section. Fig. 2 is a section at the line 2 2 on Fig. 1.

I have shown in the drawings a familiar construction and arrangement of fire-box, 25 boiler, bridge-wall, and smoke-discharge passages.

A represents the boiler; B, the grate; C, the fire-box above the grate; D, the ash-pit; E, 30 the bridge-wall at the rear of the grate; F, the smoke-discharge pipe, which leads to the smoke-stack G.

H is a damper in the smoke-discharge pipe F. Back of the damper H—that is, between 35 said damper and the furnace—a pipe J leads off from the smoke-pipe F to the intake of a fan K. In the pipe J there is interposed a cut-off valve or damper J'. Between the cut-off valve or damper J' and the fan the pipe J is provided with an air-inlet J² and a valve or damper J³, governing such air-inlet. A pipe L, leading from the discharge of the fan K, is branched or forked, one branch L' extending toward the fire-box and being again branched or forked, one branch L¹⁰ leading through the furnace-wall above the grate into the fire-box proper, and another branch L¹¹ leading through the furnace-wall into the ash-pit. The other branch L² of the 45 pipe L leads off from the lower side of said pipe L, said pipe being enlarged to form a trap-pocket L³ at the lower side and the branch L² leading from the end of this trap-pocket off to the smoke-stack G, a regulating

valve or damper M being interposed in said branch L². The purpose of this branch L¹ is to conduct the spent or perfectly-consumed gases, chiefly carbonic-acid gas, to a point beyond the damper H, and thus into the stack, while the branch L' conducts the lighter and less perfectly consumed or unconsumed gases back to the fire. The gases which are returned to the furnace through the branch L', having become mixed with air derived through the air-inlet J², are ready for perfect combustion when they are discharged into the fire, either through the branch L¹¹, causing them to pass up through the bed of coals on the grate or through the branch L¹⁰, which causes them to be discharged above the bed of coals in the fire-box proper. The means for discharging and distributing the intermixed air and returned gases which are delivered through the branch L¹⁰ above the fire consists of a reheating or superheating box or chamber N. This box or chamber is made of cast-iron and is mounted immediately above the fuel-door at the forward side of the fire-box, extending across the fire-box substantially from end to end. On the rear side this 80 box is provided with slots m m m for discharge of the mixed air and gases downward and rearward onto the fire or into the hot products of combustion rising from the bed of coals. The position of this distributing 85 and reheating box is such that it is intensely heated, and the gases returned through the pipe L' and somewhat cooled in their passage and further cooled by the intermixture of fresh air with them are reheated so as to be 90 ready for instant and perfect combustion when they are discharged into the other hot gases rising from the coals. The quantity of air which they carry, derived in their passage through the pipe L', being preferably some- 95 what more than required for their own complete combustion, and this air, as well as the gases being heated in its passage through the box N, and particularly when it is discharged through the narrow discharge-slots m, its 100 presence above the coals in the fire-box assists the combustion of the fresh gases developed from the coals, so that the proportion of imperfectly-consumed gas to be returned through the pipe L' tends to diminish some- 105 what after the return of the gases and their discharge through the box N commences.

In operating this device upon starting the

fire the damper H is left open, leaving the smoke-pipe F discharging directly into the stack; but as soon as the fire is in good operation the damper H is partly closed, the fan K set in operation, and the valve J' is opened, causing a large part of the products of combustion to be drawn through the pipe J and discharged through the pipe L. The trap or pocket L³, the particular construction of which will be hereinafter explained, being at the lower side of the pipe L and the gases being somewhat cooled by the time they have reached this point, the carbonic-acid gas and, in the main, all the gases which result from more perfect combustion settle into the lower part of the pipe L and are drawn into this trap L³ and pass out by the natural draft through the pipe L² into the stack G, leaving the remainder, comprising all the imperfectly-consumed gases, to pass through the pipe L' and be discharged in part below the grate and in part above the grate to complete their combustion by passing again through the fire-box, where the air which they carry further assists the original combustion of new fuel. The pipe J preferably takes off from the upper side of the pipe F, so that the heavier and more perfectly consumed gases coming in the first instance from the furnace and tending to follow the lower side of the pipe will pass directly into the stack, and the damper H is for like reason preferably made to close from above downward, so that when partly open the aperture will be at the lower side of the pipe. The same result may be further assisted by locating a trap F', similar to the trap L³, at the lower side of the pipe F, between the damper H and the furnace and leading a pipe F² from it to the stack, thus making a by-pass around the damper H to the stack. By this means practically all except the perfectly-consumed gases are excluded from the stack and caused to pass back over the fire until they become consumed, so as to fall into the traps L³ and F' and be discharged thence to the stack.

I claim—

1. In a furnace, in combination with the fire-box, smoke pipe and stack, a cut-off or damper in the smoke-pipe; an exhaust device and pipe connecting its intake with the smoke-pipe back of the damper having an air-inlet and means for regulating the same; a discharge-pipe from the exhaust device leading to the fire-box; a heavy-gas trap in the smoke-pipe back of the damper and a discharge connection from the trap leading past the damper for final discharge into the stack; a heavy-gas trap in the discharge-pipe 60 from the exhaust device and a branch pipe

leading from the trap having connection for discharge beyond the smoke-pipe damper into the stack.

2. In a furnace, in combination with a passage by which the smoke is conducted on its way to the stack, a damper in such passage; connections leading from such passage back of the damper for conducting the gases back to the fire-box; a heavy-gas trap located at the lower side of a substantially horizontal portion of such passage back of the damper, said trap comprising at its upper part baffle-plates trending obliquely onward and downward into the trap-space, and a discharge connection leading from the trap beyond the baffle-plates past the smoke-pipe damper for final discharge into the stack.

3. In a furnace, in combination with a passage by which the smoke is conducted on its way to the stack, a damper in such passage; a heavy-gas trap located at the lower side of a substantially horizontal portion of such passage back of the damper, said trap comprising at its upper part baffle-plates trending obliquely onward and downward into the trap-space, and a discharge connection leading from the trap beyond the baffle-plates past the smoke-pipe damper for final discharge into the stack; an exhaust device and a pipe connecting its intake with said horizontal portion of the smoke-pipe at the upper side thereof back of the damper, and a discharge-pipe from said exhaust device leading to the fire-box.

4. In a furnace, in combination with a passage by which the smoke is conducted on its way to the stack, a smoke cut-off or damper in the smoke-pipe; an exhaust device; a pipe connecting its intake with the smoke-pipe back of the damper and having an air-inlet and means for regulating the same; a discharge-pipe from the exhaust device leading to the fire-box having a substantially horizontal portion and a heavy-gas trap located at the lower side of said substantially horizontal portion, said trap comprising at its upper part baffle-plates trending obliquely onward and downward into the trap-space, and a discharge connection leading from the lower side of the trap past the smoke-pipe damper for final discharge into the stack.

In testimony whereof I have hereunto set my hand, in the presence of two witnesses, at Chicago, Illinois, this 11th day of September, 1905.

JOHN P. McLEOD.

In presence of—

L. M. SMITH,
J. S. ABBOTT.
